UNITED STATES PATENT OFFICE

2,616,511

TURBO-PROPELLER

William Perrott, North Bergen, N. J., assignor, by direct and mesne assignments, to Trochoidal Propellers, Incorporated, a corporation of Delaware

Application June 3, 1948, Serial No. 30,829

4 Claims. (Cl. 170—166)

1

The specification which follows relates to an improvement in propellers for ships and airplanes and impellers for liquid pumps, fans and the like.

The conventional and generally adopted theory of propeller fans and the like is based upon an Archimedian screw. This presupposes a spiral thread of a helix or a plurality of such which occupy a cylindrical space around the axis of a rotating drive shaft. Devices of this type are characterized by a flow of fluid which while being received in an axial direction is discharged and deflected away from that direction. There results a zone of low pressure in the axial region behind the propeller and an undesirable disturbance is caused by the discharge of the fluid flow of the stream in a divergent path.

The present invention differs basically in that the novel turbo-propeller while receiving the stream in an axial direction diverts it to a minimum extent and restricts the line of discharge of propulsion to parallelism with the axis.

One of the objects of the invention is to utilize the principle of trochoidal action, for with the curvilinear design on the suction side, propeller efficiency is improved, turbulence reduced, thereby totally eliminating back pressure, making possible air or fluid motion across the moving blade equal to the rotating blade velocities. In trochoidal action we approach perfection in propeller efficiency, for we arrive at a point where a condition has been created where the outflow is equal to the entrance flow, which condition can only be obtained by a curve which is generated by a point on a circle which rolls on a straight line, and admits of rotation on a longitudinal axis.

The effect of combining the hemispherical rotor with the generally radial blades, is to effect a negative pressure (vacuum) at or near the axis, for every thread of the turbo-propeller in its spherical spiral cut has a motion clearly different from that produced by other propulsing and revolving bodies, for (a) the cone effectively has a spiral (helix) outsetting from the vortex and developing interminably (endless core) in co-axial diverging spirals and (b) the turbo-cylinder, however, propelling and advancing at uniform velocity will effect a motion of subservience to carry off current of helicoidal spirals.

It thus follows that an object attained by this invention is to produce a longitudinal vortex flow which will lower the pressure at the axis and thus lower cavitation.

A still further object of the invention, in giving the blades the concave and convex shape on the

thrust and suction sides respectively, so that the thickness may be smaller than the other types of propellers, is to reduce its resistance at the point or entrance of penetration, thus increasing power of the thrust of the central rectilinear vortex, created and maintained by effect of induction.

By way of example and without limitation, the invention has been illustrated in the accompanying drawings in which:

- 10 Fig. 1 is a rear elevation of the improved propeller;
 Fig. 2 is a side elevation of the same.
 Fig. 3 is a longitudinal section on line 3—3 of Fig. 1;
 15 Fig. 4 is a diagrammatic view of the fluid current through the propeller, and
 Fig. 5 is a view in cross-section, of the blade taken on line 5—5 of Fig. 3.
 The above objects of the invention are obtained
 20 by an improved design for both the rotary shell and the radial blades.
- As illustrated, the propeller is shown to comprise a central hub 1 which has a stream-line tip 2. The hub is, of course, rigidly attached to the propelling or drive shaft. A part-spherical rotor 9 is provided. This is specifically a zone of a sphere comprised between parallel planes one of which is substantially the maximum diameter of the sphere.
- 25 30 This zone or rotor is held in a position axially of and spaced from the driving shaft. The support consists of the bases 10 of the blades 11. The blades are therefore rigidly supported by the zone 9 which forms a circumferential reinforcement between the intermediate parts of the blades.

As shown in Figs. 2 and 3 the leading edge 12 of each blade is curved to the rear or in the direction of fluid flow and may be considered as 35 travelling in a path such as would be generated by the rotation of a circle around its diameter or of a parabola around its axis.

Each blade is inclined from the front edge to the rear edge to provide the desired variable pitch 40 with respect to the axis of rotation. Furthermore, as shown in Fig. 5 the blades are made concave on their thrust or rear surfaces. The effect of this is to enhance the longitudinal factor of propulsion.

50 Each blade has a tip 13. These tips are flatter, more perpendicular to the axis of rotation and angularly disposed with respect to the blades in general. The tips provide for additional thrust against the air or fluid. This thrust admits of 55 rotation on a longitudinal axis.

In Fig. 4 there is shown by dotted lines the effects produced by the particular configuration or zone member and the individual blades. Thus those streamlines 14 which are met by the advancing edges of the propeller parts will be slightly diverted. A part of the flow passes between the hub 7 and the zone member 9. Due to the convexity of the latter the flow is returned to an axial direction as shown.

That portion of the flow which is outside of the zone member 9 will be met by the concave rear side of the blades 11. Thus the outward direction of the flow is corrected and it is returned to parallelism with the axis.

Due to the maintenance of parallelism of the flow past the members 9 and 11, the thrust of the blade tips 13 is not disturbed by the flow from the remaining parts of the propeller. Thus the thrust from the blade tips will be substantially axial. In carrying out the above arrangement it will be apparent that maximum efficiency is realized by the conjoint use of the several specific elemental details. Comparison of the present design with comparable known propellers is indicated in the following table:

	Turbo- Pro- peller	Comparable devices
Maximum diameter in meters (D)	0.330	0.120
Geometrical pitch in meters (P)	0.276	0.096
Number of blades	3	3
Diameter of hub (d)	0.066	0.020
Developed area of surface (S _d)	0.03818	0.00475
Ratio pitch to diameter (P/d)	0.836	0.80
Ratio surface area to diameter $\frac{S_d}{4D^2}$	0.446	0.42
Thickness radial section q	0.0112	0.005
Immersion of axis (draught) I	0.330	0.120
		0.005

Given a rotation of 77.5 revolutions per minute, a propeller of one meter diameter advancing one meter per second has an efficiency of 68.6 per cent, while for a normal screw propeller the maximum is about 62 per cent.

Propellers constructed in accordance with the improved design give added velocity to the fluid stream thus producing greater propulsion. At the same time there is less cavitation due to the longitudinal direction of the discharged stream. The specific construction of the blades with thin design and reduced mass and with concave cross section is a decided factor in the improved results obtained.

While the preferred form of the invention has been described and illustrated for the purpose of example, it will be readily apparent that many changes may be made in sizes, proportions and materials without departing from the scope of the invention as defined in the following claims.

What I claim is:

1. A propeller comprising a hub, a plurality of rearwardly inclined blades attached to the hub, a rotor in the form of a zone of a sphere with opposite openings of different sizes mounted on the blades concentric to the hub and spaced

therefrom with its smaller opening in front, said rotor being substantially as wide as the blades at the point of mounting, and the major portion of the leading edges of the blades lying in a spherical path of revolution.

2. A propeller comprising a hub, a plurality of rearwardly inclined blades attached to the hub, a rotor in the form of a zone of a sphere with opposite openings of different sizes mounted on the blades concentric to the hub and spaced therefrom with its smaller opening in front, said rotor being substantially as wide as the blades at the point of mounting, and the major portion of the leading edges of the blades lying in a spherical path of revolution, and relatively flat tips on the blades extending radially in planes substantially at a right angle to the axis of the hub.

3. A propeller comprising a hub, a plurality of rearwardly inclined blades attached to the hub, a rotor in the form of a zone of a sphere with opposite openings of different sizes, mounted intermediately on the blades concentric to the hub and spaced therefrom with its smaller opening in front, said rotor being substantially as wide as the blades at the point of mounting, and the blades in cross-section being concave on their rear surfaces.

4. A propeller comprising a hub, a plurality of rearwardly inclined blades attached to the hub, a rotor in the form of a zone of a sphere with opposite openings of different sizes, mounted intermediately on the blades concentric to the hub and having its smaller opening in front, said rotor having an inner surface that is concave from front to back diverting the fluid stream into a direction parallel to the hub axis.
